UNITED STATES PATENT OFFICE.

HANS PRILLWITZ, OF FRANKFORT-ON-THE-MAIN, GERMANY, ASSIGNEE TO I. G. FAR-BENINDUSTRIE AKTIENGESELLSCHAFT, OF FRANKFORT-ON-THE-MAIN, GERMANY.

MIXING APPARATUS.

Application filed August 20, 1925, Serial No. 51,470, and in Germany August 29, 1924.

This invention relates to improvements in apparatus for mixing liquids, including emulsions and suspensions with each other, which apparatus resemble rotary pumps or turbines in which a wheel provided with 5 vanes or blades is rotated by an outer driving mechanism. The improvement bears relation to the especial manner of supplying the rotary wheel with the materials to be mixed.

An apparatus of the type described and embodying my invention is shown in the accompanying drawing, in which

Fig. 1 is a vertical cross-section along the 15 driving shaft of the machine;

Fig. 2 is a vertical cross-section through the rotor, and

Fig. 3 is a diagrammatic side view on a reduced scale of a modification.

1. 1 is the casing of the mixer, 2 is the rotor provided with two rows of vanes or blades 3 and 4. The outer vanes or blades may be offset with respect to the inner vanes or blades as shown in Fig. 2. 2' is the rotating 25 shaft, 5 illustrates the pipe for supplying the material to be treated.

In the interior of the mixing apparatus the outer diameters of the supply pipe and the inner row of blades or vanes (or, when 30 more than two rows are employed, the innermost row) are almost equal. The inner diameter of the discharge pipe 6 is preferably chosen to differ from that of the supply pipe.

35 The front side of the latter is closed by a cover 7, and its wall is perforated by slots 8, very close to which the blades or vanes 3 rotate. The total cross-section of the said slots preferably amounts to at least the cross-section of the supply pipe, but it may be increased or diminished by means of a slotted ring 9, according to the nature of the material under treatment. 10 is a pipe provided with a valve 11 for connecting the 40 interior of casing 1 with a suction pump (not shown). The dimensions of the casing are reduced as much as possible so that only a little more than the space required for the rotation of the wheel is left.

50 The apparatus is operated in the following manner. After the casing has been filled with liquid, the rotor is set revolving by a suitable motor. The material to be treated, for instance a liquid and a powder 55 to be suspended therein, is coarsely mixed

in a container 12. Owing to the sucking action of the machine, which may be assisted by external pressure, or owing to external pressure alone, the mixture is lifted and supplied to the mixer through pipe 5. 60 The material may be returned to container 12 through pipe 6 and the treatment continued until the desired intimate union of the mixture is attained; or the discharge pipe may be connected with another vessel 65 or vessels 13, as shown in Fig. 3, and the mixture discharged into these vessels after one single passage through the mixing machine. When a plurality of liquids is to be supplied to the mixer at the same time, the 70 supply pipe may be connected with a corresponding number of supply pipes and containers 12^a and 12^b for instance (Fig. 3).

The material to be mixed is projected from the slots 8 at the end of pipe 5 in the 75 form of radial jets which are immediately cut off by the blades or vanes of the rotor.

The advantages of my improved apparatus as compared with the known appliances of similar kind are above all attributable to 80 the fact that the efficiency as to quantity and intimate union of the mixture is multiplied. Furthermore the economy is increased owing to the fact that according to my invention relatively small machines are capable of conveying and mixing large quantities of material to be treated. By proportionating the cross-sections of the supply pipe and the delivery pipe I may adjust the 85 conveying action with respect to the mixing 90 action thus paying attention to the occasional requirements.

My improved machine is especially distinguished by a special security of working, inasmuch as the stuffing-box for the 95 rotor shaft is situated at the pressure-side of the circulating liquid, whereby uninterrupted working and tender treatment of the stuffing-box is warranted.

My improved apparatus may also be employed for treating thick or pasty materials, owing to the relatively wide slots in the 100 supply pipe.

I claim:

1. Mixing apparatus of the turbine or 105 centrifugal pump type, comprising a casing, a paddle-wheel in the said casing rotated by an external driving mechanism, a supply pipe having an inner diameter approximating the inner diameter of the paddle-wheel 110

and extending into the interior cylindric opening of the said paddlewheel, the end of the said supply pipe being provided with a large number of slots in the proximity of the paddles of the said wheel, and a pipe extending from the delivery side of the said paddle-wheel.

2. Mixing apparatus of the turbine or centrifugal pump type, comprising a casing, 10 a paddle-wheel in the said casing rotated by an external driving mechanism, a supply pipe having an inner diameter approximat-

ing the inner diameter of the paddle-wheel and extending into the interior cylindric opening of the said paddle-wheel, the end of the said supply pipe being provided with a large number of slots in the proximity of the paddles of the said wheel, and a pipe extending from the delivery side of the said paddle-wheel and having a cross-section 15 smaller than the cross-section of the supply pipe.

In testimony whereof I affix my signature.
HANS PRILLWITZ.
